UNITED STATES PATENT OFFICE

132,969

DESIGN FOR A PLATE FOR HOLDING AND HANDLING EDIBLE SPAGHETTI

James B. Whittaker, Rochester, N. Y.

Application April 28, 1942, Serial No. 106,737

Term of patent 14 years

To all whom it may concern:

Be it known that I, James B. Whittaker, a citizen of the United States, residing at Rochester, in the county of Monroe and State of New York, have invented a new, original, and ornamental Design for a Plate for Holding and Handling Edible Spaghetti, of which the following is a specification, reference being had to the accompanying drawing, forming a part thereof.

In the drawing:

ing and handling edible spaghetti, showing my design.

Figure 2 is a side elevational view.

I claim:

The ornamental design for a plate for holding and handling edible spaghetti, substantially as shown.

JAMES B. WHITTAKER.
